UNITED STATES PATENT OFFICE.

THOMAS GHOLSON VIVION, OF COLUMBIA, MISSOURI.

DESIGN FOR A BADGE OR BUTTON.

SPECIFICATION forming part of Design No. 26,453, dated December 29, 1896.

Application filed October 3, 1896. Serial No. 607,805. Term of patent 3½ years.

To all whom it may concern:

Be it known that I, THOMAS GHOLSON VIVION, a citizen of the United States, and a resident of Columbia, in the county of Boone and State of Missouri, have invented and produced a new and original Design for Badges or Buttons, of which the following is a specification, reference being had to the accompanying drawings, showing a part hereof.

10 Figure 1 is a side elevation of a badge or button, showing my design. Fig. 2 is an edge view showing the badge as a button.

The leading feature of my design consists in the representation of a foot-ball with an imitation row of stitches extending across the face of the same, thus forming two panels or spaces, the picture of a tiger or of a tiger's head in one of the panels or spaces, and a marginal band or border around the edge of 15 the representation of the foot-ball.

20 In the drawings, the letter A indicates the badge, which in full view represents a part of a foot-ball, the badge being of oval form.

Across the face of the representation of the foot-ball is an imitation row of stitches at B, 25 which divide the face of the foot-ball into two panels or spaces. As shown, the imitation row of stitches is placed to make the upper panel or space of smaller area than the lower panel or space, but the order may be reversed 30 by changing the position of the imitation row of stitches. In one of the panels or spaces is the pictorial representation of a tiger or of a tiger's head C.

The representation of the foot-ball is surrounded by a narrow marginal band D. This band and the row of stitches are colored in old gold, while the foot-ball is black.

What I claim is—

35 The design herein shown and described for a badge or button, as set forth.

THOMAS GHOLSON VIVION.
